UNITED STATES PATENT OFFICE

2,488,591

ELECTRICALLY HEATED APPLICATOR

Anna Fevas, Akron, Ohio

Application January 7, 1947, Serial No. 720,580

7 Claims. (Cl. 128—24.1)

1

This invention relates to an electrically heated applicator.

An object of this invention is to provide a novel and efficient applicator for applying heat and liquid simultaneously to the skin, and the applicator is primarily intended to be used in giving beauty facial treatments.

Another object is the construction of a novel applicator for applying heat to the face and neck, thereby opening the pores, and at the same time releasing a certain amount of liquid and massaging the same into the open pores.

A still further object of this invention is the construction of an applicator, which, at the time that the skin is being massaged, will allow oil to penetrate into the pores, causing the skin to assume a finer texture; this treatment removes all dirt and foreign matter from the pores.

This application discloses improvements over the invention disclosed in my prior patent, No. 2,385,501, issued September 25, 1945, "Electrically heated applicator."

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in side elevation of an electrically heated applicator constructed in accordance with the present invention.

Figure 2 is an enlarged, fragmentary, vertical, central, sectional view of the applicator.

Figure 3 is a sectional view, taken on line 3—3, Fig. 2, and looking in the direction of the arrows.

Figure 4 is an enlarged, longitudinal, sectional view of the handle of the applicator.

Referring to the drawings, in which the preferred embodiment of this invention is illustrated, 1 designates the body, 2 is the hollow neck, and 3 is the handle of the applicator.

The body 1 comprises a primary section 4 with an auxiliary or cap section 5 thereon. The hollow neck section 2 is fixedly secured in any suitable manner to the auxiliary section 5. At the center of the primary section 4 is an upstanding annular flange 6, which receives the lower or outer end of the primary sleeve 7, Fig. 2. The flange 6 and sleeve 7 are fixedly secured together by any ordinary means. The primary sleeve 7 extends above the cap or auxiliary section 5, and the extended end is externally threaded, and on this threaded portion is threaded the auxiliary sleeve 8 (Fig. 2). The auxiliary sleeve 8 is normally tight against the auxiliary section 5, whereby the primary section 4 and auxiliary section 5 are securely fastened together. In the lower end of the primary sleeve 7 is an annular bottle rest 9. A thread screw 10 extends

through the primary sleeve 7 and annular bottle rest 9. This screw 10 performs a dual function, to wit: it securely holds the bottle rest 9 in position and at the same time acts as a thread for threading the container or bottle 11 into position. The bottle 11 is provided with threads 12 that are screwed upon the inner end of screw 10 when the bottle is being positioned within the applicator.

A brake device is provided for securely holding the bottle 11 in position against accidental displacement. This brake device comprises a coil spring 13 (Fig. 3) that surrounds the lower portion of the primary sleeve 7. This spring 13 has a V-shaped portion 14 that normally extends through registering apertures in sleeve 7 and bottle rest 9; this V-shaped portion is normally positioned between two contiguous threads on the bottle 11 (Fig. 2). Therefore, there is always a binding action, in the nature of a brake, exerted on the inserted bottle, which prevents the bottle from having accidental movement.

The handle 3 of the applicator comprises a cylindrical casing 15 on the ends of which are mounted outer cap 16 and inner cap 17. Threaded into the inner cap 17 is the hollow neck 2. This hollow neck extends into the cylindrical casing 15 beyond the inner face of the inner cap 17. Extending into the outer cap 16 is an externally threaded sleeve 18. On the inner ends of the hollow neck 2 and sleeve 18 is threaded the fibre tubing 19. A lock ring 20 is on sleeve 18 against the outer face of the outer cap 16. Within the fibre tubing 19 is a fixed plate 21. A regulator screw 22 is mounted on the fibre tubing 19. This screw 22 is to adjust the switch blade 23, as the operator desires. The inner end of the switch blade 23 is fastened to the fibre tubing 19 by small bolts 24. A slideable switch plate 25 (Fig. 1) is mounted on the cylindrical casing 15 and integral with this switch plate 25 is a contact lug 26, whereby sliding adjustment of the switch plate 25 longitudinally of the handle will cause the contact lug to either move away from contact with the switch blade 23 or into contact therewith for closing the circuit. The wire 27 is passed into the fibre tubing 19 and thence wound around said tubing in a coil at 28 and thence passed to the left and into the hollow neck 2 and body 1, forming a heating coil 29, as clearly shown in Fig. 2. The wire 30 is passed into the fibre tubing 19 and is fastened under the nut on one of the bolts 24. Under contact lug 26 is the fixed plate 21. The inner end of wire 31 is fastened under the fixed plate 21 (Fig. 54), whereby when the contact lug 26 is in engagement with the switch blade 23, a complete circuit is created so that electricity is supplied to the heating coil 29, resulting in the body 1 and the liquid contained in the bottle 11 being heated, 60 as the operator desires.

2

In Fig. 3, a fluid control device is indicated at 32, Fig. 3. This fluid control device is in the container or bottle 11 and the detailed construction of this device 32 is specifically disclosed in my copending application filed January 7, 1947, Serial No. 720,579.

The wires 27 and 30 are a part of an ordinary electric plug device, whereby the applicator can be supplied with electricity by plugging in any outlet of a dwelling or building.

When it is desired to take the applicator apart, the operator first removes the lock ring 20 and then the cap 16, whereupon the cap 17 with the fibre tubing 19 and sleeve 18 can be removed from the cylinder casing 15. If the fibre tubing 19 is to be examined, the removal of the sleeve 18 and the hollow neck 20 will permit inspection of the interior of said fibre tubing 19.

When it is desired to examine the interior of the hollow body 4, the operator first removes the auxiliary sleeve 8 and then lifts off the auxiliary section 5, resulting in the exposure of the interior of the primary section 4.

I have found from practical experience that this applicator produces excellent results, is easily manipulated, and is durable in construction.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an electrically heated applicator, the combination of a body provided with a primary sleeve and an annular bottle rest within said primary sleeve, a thread screw extending through said primary sleeve and annular bottle rest, said screw extending into the space between the walls of said bottle rest, a bottle in said primary sleeve and screwed upon the extended end of said screw, and electrically heated means in said body around said primary sleeve.

2. In an electrically heated applicator, the combination of a hollow body provided with a primary sleeve, a bottle rest within said primary sleeve, a bottle provided with screw threads resting upon said bottle rest, said primary sleeve and bottle rest provided with brake means engaging said bottle between two portions of the thread thereon, and said body provided with electrically heated means around said primary sleeve.

3. In an electrically heated applicator, the combination of a hollow body provided with a centrally located primary sleeve, an annular bottle rest in the lower end of said primary sleeve, a bottle provided with threads resting on said annular bottle rest, said primary sleeve and annular bottle rest provided with registering slots contiguous to said threads on said bottle, a coil spring around said primary sleeve, said spring provided with a V-shaped portion, said V-shaped portion extending through said registered apertures and normally in engagement with the threaded portion of said bottle, and electrically heated means in said body.

4. In an electrically heated applicator, the combination of a body provided with bottle-receiving means at the center, said bottle-receiving

means including a screw constituting a thread, a bottle within said bottle-receiving means and threaded upon said screw, said bottle-receiving means provided with brake means, normally pressing upon a portion of said bottle, and electrically heated means in said body contiguous to said bottle-receiving means.

5. In an electrically heated applicator, the combination of a body provided with bottle-supporting means, a neck fixedly secured to said body, a handle, said handle provided with an inner and an outer cap, said neck screw-threaded through said inner cap with its inner end extending into said handle, a screw-threaded sleeve extending through said outer cap and into said handle, a fibre tubing threaded on the extended portion of said neck and the extended portion of said sleeve, a switch within said fibre tubing, and wires connected to said switch and extending through said neck into said body around said bottle-supporting means.

6. In an electrically heated applicator, the combination of a body provided with bottle-supporting means, a hollow neck fixedly secured to said body and provided upon its outer end with screw threads, an inner cap mounted upon the screw-threaded portion of said neck, a cylindrical casing detachably mounted on said inner cap, an outer cap detachably mounted on said cylindrical casing, said threaded portion of said neck extending into said cylindrical casing, said outer cap provided with an externally threaded sleeve, said externally threaded sleeve extending into said cylindrical casing, a fibre tubing threaded on the extended portions of said neck and said sleeve, a switch within said fibre tubing, manually operated means on the outside of said cylindrical casing and cooperating with said switch for actuating the same, and wires extending into said fibre tubing and connected to said switch and also extending through said hollow neck and positioned contiguous to said bottle-supporting means.

7. In an electrically heated applicator, the combination of a hollow body comprising a primary section, an auxiliary section on said primary section, a primary sleeve secured to said primary section, said primary sleeve extending through said auxiliary section and above same, said primary sleeve being externally threaded above said auxiliary section, an auxiliary sleeve threaded on the upper threaded end of said primary sleeve, said auxiliary sleeve being adapted to press tightly against said auxiliary section, whereby said sections are securely held together, a bottle in said primary sleeve, and means in said hollow body for heating said bottle.
